UNITED STATES PATENT OFFICE

2,680,211

SEQUENCE PULSE STARTING CIRCUIT FOR
FLUORESCENT LAMPSJohn H. Campbell, Painesville, Ohio, assignor to
General Electric Company, a corporation of
New York

Application March 14, 1950, Serial No. 149,536

3 Claims. (Cl. 315—96)

1

This invention relates generally to the starting and control of electric discharge devices, such as low pressure positive column lamps of the fluorescent type, and more particularly to circuits suitable for use with fluorescent lamps which require preheat of their thermionic cathodes at starting.

My invention is concerned with the series operation of fluorescent lamps from a voltage source, of which the terminal voltage is insufficient to start a discharge by means of the usual inductive surge switch-start circuit, and is applicable to both alternating and direct current circuits.

It is an object of my invention to provide a new and improved starting and operating arrangement for fluorescent lamps provided with at least one thermionic electrode, which arrangement employs a minimum of equipment and assures reliable starting, together with efficient operation.

Another object of my invention is to provide an improved starting arrangement for fluorescent lamps which allows the sum of the voltage drops across the lamps during operation to be a high proportion of the line voltage, thereby insuring a high operating efficiency.

One of the features of my invention is the provision, in the starting circuit, of transforming means such as an ignition type pulse transformer, of which a primary winding portion is connected in series with the discharge circuit of a number of fluorescent lamps. A secondary winding portion of the pulse transformer is connected to an auxiliary starting electrode or capacitive plate associated with each lamp. The filamentary electrodes in the lamps are in series with a resistance and a switch device preferably of the glow or of the thermal type, in order to allow pre-heating of the electrodes at starting. Such circuit connections may be extended to include any number of lamps, depending upon the magnitude of the supply voltage. In starting, whenever one of the switches opens, a pulse is generated by the pulse transformer which is applied to the capacitive plates of all the lamps, including the lamp whose associated switch operated to produce the pulse. The lamp in question then starts and the other switches successively open until all the lamps have started, a pulse being generated at the opening of any one switch to start its associated lamp.

For further objects and advantages and for a better understanding of my invention, attention is now called to the following description and to the accompanying drawing. The features of my invention believed to be novel will be more particularly pointed out in the appended claims.

2

In the drawing:

Fig. 1 is a schematic diagram of a starting circuit embodying my invention and illustrating the operation of two fluorescent lamps in series from a direct or alternating current source.

Fig. 2 is a schematic diagram of another circuit embodying my invention, modified to permit the use of thermal type switches rather than the glow type illustrated in Fig. 1.

10 Referring to Fig. 1, the circuit therein comprises a pair of fluorescent lamps 1, 1' electrically connected in series with each other and with a ballast resistance 2 across a pair of input terminals 3, 3' adapted to receive either alternating or direct current. The devices 1, 1' are positive column discharge lamps comprising essentially an evacuated glass envelope containing a mixture of argon at a pressure of a few millimeters along with a small quantity of mercury. The electrodes 15 4, 5 and 4', 5' sealed into the ends of the lamps may consist of coils of tungsten wire coated with activated electron emitting materials such as barium and strontium oxides. If desired, each of the devices 1, 1' may be a commercial low pressure fluorescent lamp wherein the envelope is coated internally with a suitable luminescent material. The ballast resistance 2 preferably has a positive temperature coefficient of resistance in order to provide good current regulating characteristics and may, as illustrated, consist of an incandescent tungsten filament lamp.

One terminal of electrode 4 in lamp 1 is connected, by means of a shunting circuit, to a terminal of electrode 5. This shunting circuit comprises a resistance 6 and a switch 7 which may be of any suitable type, either manually or automatically operable. For instance, I have illustrated a glow type switch comprising a glass envelope 8 containing an ionizable gas such as neon and including therein a pair of electrodes 17 and 18, electrode 18 consisting of a curved bimetallic strip.

40 In its normal position, electrode 17 does not make contact with electrode 18; however, when a sufficient voltage is applied across the glow tube, a discharge occurs therein which heats up the electrodes and causes the curved end of electrode 18 to bend over and make contact with electrode 17, whereupon the switch is closed and, a short circuit being formed, the glow ceases. After a brief interval of time, the electrodes cool whereupon they separate once more, and the circuit is opened. After lamp 1 starts, the voltage drop across it is less than the ionizing potential of the gas within the glow switch. Accordingly, no glow occurs, the electrodes do not become heated, and the switch stays permanently

opened. Lamp 1' is provided with a similar shunting circuit comprising a resistor 6' and a glow switch 7'.

In accordance with my invention, I provide a pulse transformer 9 which may be a small ignition type autotransformer. The primary portion 10 of transformer 9 is connected in series with the discharge circuit between the terminals 3, 3' and the lamps 1, 1' and the secondary portion 11 is connected to capacitive plates 12, 12' located approximately at the mid-points of the glass envelopes of lamps 1, 1', respectively.

In operation, when line voltage is first applied to terminals 3, 3', the glow switches 7, 7' operate and, after a brief interval, close, which provides circuit continuity through the filamentary electrodes of the lamps. The circuit at this instant may be traced from terminal 3, through the tungsten lamp ballast 2, through primary portion 10 of transformer 9, through electrode 4, resistance 6, glow switch 7, and electrode 5, then through electrode 4', ballast 6', glow switch 7' and electrode 5' back to terminal 3'. The current flowing through the electrodes causes them to heat up and shortly thereafter switches 7 and 7' will have cooled sufficiently to reopen. Since, due to normal tolerances in manufacturing, no two switches will be identical and open at exactly the same instant, it will be assumed, for ease of explanation, that switch 7 opens first. When this occurs, current is momentarily interrupted in the primary portion 10 of autotransformer 9. The sudden interruption of current therein induces a pulse of voltage in secondary portion 11 which is applied by means of the capacitive plates 12 and 12' across the gaseous atmosphere within the lamps 1, 1'. This causes an ionization of the gas within the lamps and the arc strikes in lamp 1. Lamp 1' is not affected as yet since its starting switch is still closed. When glow switch 7' opens, a second pulse is generated in the same way and lamp 1' starts. Both the inductive surge due to the rupture of the primary circuit of transformer 9, and the induced pulse in the secondary, are effective in striking the arc. The purpose of the resistances 6 and 6' in series with the contacts of each glow switch is to limit the preheat current to a value which will not cause an over-voltage condition across tungsten ballast lamp 2 when the glow switches are closed. Under low voltage conditions, where the sum of the striking voltages of the two glow switches approaches or is greater than the line voltage, it may be desirable to shunt one of the switches by a resistance. Thus, placing a resistance 19 (shown in dotted lines) in parallel with switch 7', insures that switch 7 will strike and start lamp 1 first, after which switch 7' will strike and start lamp 1'. Although I have illustrated the arrangement as applied to two lamps, it can obviously be applied to a greater number of lamps with ensuing advantages and economy. Thus, only one pulse coil is required for any number of lamps connected in series across a source. The ignition pulse coil, moreover, generates a high pulse voltage at starting only, so that although the primary portion thereof must be designed to carry the discharge current, the secondary portion may consist of very fine wire since it carries only a negligible current, and that current only at the very instant of starting. Such transformers can be made very small since the energy required to ionize the gas in the lamps with a pulse applied through an external electrode is negligible, being of the order of milliwatts.

Referring to Fig. 2, I have illustrated therein another embodiment of my invention which may be utilized to advantage in operating fluorescent lamps from electrical circuits where the terminal voltage is so low as to preclude the use of glow switches. Like reference numerals in this figure denote corresponding circuit elements as in Fig. 1. In this circuit, I have substituted thermal type switches 13 and 13' for the glow switches 7 and 7' of Fig. 1. These switches are thermally associated with a small heating coil or resistance 14 which is inserted in series with the main discharge circuit. Switches 13 and 13' comprise a pair of contacts and bimetallic members 15 and 15', which, upon being heated, bend away from their associated contacts, thereby opening their respective shunting circuits. The remainder of the circuit is in all other respects identical to that of Fig. 1.

The operation of this circuit is similar to that of Fig. 1 and differs only in the following details: when voltage is initially applied to terminals 3, 3', the thermal switches being in their normally closed position, current flows through the heating coil 14 and also through the filamentary electrodes of the lamps 1, 1'. The bimetallic members of switches 13, 13' heat up and open, the instant of the open circuit occurring at slightly different times for each switch in normal course. When either of the switches opens, a pulse is generated which starts the discharge in the lamp associated with that particular switch. When the lamps are lit, the discharge current which must flow through resistor 14 keeps the thermal switches heated and accordingly opened. When the lamps are turned off, the switches gradually cool and, in due course, reclose thereupon assuming the position required for the next lighting operation.

Referring to Fig. 3, the pulse coil therein illustrated shows an actual construction which I utilize to operate two 35-watt fluorescent lamps of the ordinary commercial variety from a 220-volt alternating current circuit. The dimensions of the coil are 2½" length by ¾" diameter with primary consisting of 150 turns of No. 28 wire and secondary consisting of 8000 turns of No. 41 wire. This coil demonstrates, in rather striking fashion, the compactness and economy of equipment possible with my invention. The ballast resistance 2 for this particular combination consists of a 200-watt, 115-volt tungsten filament lamp.

While certain specific embodiments have been shown and described, it will, of course, be understood that various modifications may be made without departing from the invention. Thus, the circuit may equally well be used with lamps having but one thermionic electrode when operated from a direct current source; or if two thermionic electrodes are provided, one may be left unheated and the lamp subsequently turned about in its sockets when the first electrode has reached the end of its life. Likewise, while a pulse coil wound as an autotransformer has been illustrated as the transforming means, it is apparent that other well known equivalents may be utilized. The appended claims are, therefore, intended to cover any such modifications coming within the true spirit and scope of the invention.

What I claim as new and desire to secure by Letters Patent of the United States is:

1. Starting and operating apparatus for gaseous electric discharge devices having therein spaced main electrodes at least one of which is thermionic and adapted to be heated by the passage of

current therethrough prior to the starting of said devices, comprising a plurality of said devices, an auxiliary starting electrode for each device, a voltage source, a ballasting impedance, a pulse coil having a primary portion and a secondary portion connected in series, a main discharge circuit including said ballast impedance and the primary portion of said coil and said devices connected in series across said source through one side of their thermionic electrodes, a shunting circuit for each device comprising a switch connecting the other side of the thermionic electrode to the other main electrode, said switches comprising means causing them to open in response to current flow in said main circuit and being non-identical in order to have slightly different physical operating characteristics causing them to open successively, and connections from the outer end of said secondary portion to the auxiliary starting electrodes of said devices.

2. Starting and operating apparatus for gaseous electric discharge devices having therein spaced thermionic electrodes adapted to be heated by the passage of current therethrough prior to the starting of said devices, comprising a plurality of said devices, an auxiliary starting electrode for each device, a voltage source, a ballasting impedance, a pulse coil having a primary portion and a secondary portion connected in series, a main discharge circuit including said ballast impedance and the primary portion of said coil and said devices connected in series across said source through one side of their thermionic electrodes, a shunting circuit for each device comprising a thermal switch connecting together the other sides of its thermionic electrodes, said switches having a heating element included in said main discharge circuit and being non-identical in order to have slightly different operating characteristics causing them to open successively, 40

and connections from the outer end of said secondary portion to the auxiliary starting electrodes of said devices.

3. Starting and operating apparatus for low pressure discharge lamps having spaced thermionic filamentary electrodes adapted to be heated by the passage of current therethrough prior to the starting of said lamps, comprising a plurality of said lamps, an auxiliary starting electrode for each lamp, a voltage source, a ballasting resistance, a pulse autotransformer having a primary portion and a secondary portion, a thermal switch comprising a set of normally closed contacts for each lamp and a resistance heater therefor, a main discharge circuit including said ballast impedance and said primary portion and said resistance heater, and said devices connected in series across said source through one side of their thermionic electrodes, a shunting circuit for each lamp including one of said sets of contacts connected between the other sides of its thermionic electrodes, said switches being non-identical in order to have slightly different operating characteristics causing them to open successively, and connections from the outer end of said secondary portion to said auxiliary starting electrodes for providing successive pulses of voltages, consequent upon the opening of said switches, to ionize each lamp in turn.
